UNITED STATES PATENT OFFICE

CLAYTON E. FREDERICKSON, OF COALINGA, CALIFORNIA, ASSIGNOR OF ONE-FOURTH
TO HOLMES H. HENSHAW, OF COALINGA, CALIFORNIA.

ATTACHMENT FOR HOISTING-DRUMS AND WINCHES.

1,000,084.

Specification of Letters Patent. Patented Aug. 8, 1911.

Application filed October 10, 1910. Serial No. 586,936.

To all whom it may concern:

Be it known that I, CLAYTON E. FREDERICKSON, residing in Coalinga, in the county of Fresno and State of California, have invented an Improvement in Attachments for Hoisting-Drums and Winches, of which the following is a specification.

My invention has for its object to provide an attachment for winches and hoisting drums designed particularly for use in well drills, whereby the driller can raise or lower the rotary drilling apparatus by hand so as to enable him to drill throughout the smallest fraction of an inch.

It is necessary when drilling with a rotary drill through rock that has a pitch, from the horizontal, to just permit the bit to touch at the beginning of the drilling operation until the bit gets a full cutting start or else the bit creeps to one side or the other thereby causing a crooked hole, *i. e.* one not directed vertically downward.

The invention resides in providing a large gear on the side of the drum or on the drum shaft, and a worm gear on a shaft one end of which shaft is pivoted while the other end is mounted in a rise and fall bearing and carries a hand wheel and crank so that the drum may be turned when the worm and gear are in mesh, or when the hand power is not used the worm shaft may be swung up to unmesh the worm and the gear, means being provided for holding the rise and fall bearing in either of its positions.

In its more subordinate nature, the invention also includes those novel details of construction, combination and arrangement of parts all of which will first be fully described and then be specifically pointed out in the appended claim, reference being had to the accompanying drawings in which,

Figure 1, is a perspective of the hoisting drum to which my invention applies. Fig. 2, is an end elevation of the same. Figs. 3 and 4 are detail views of the rise and fall bearing and its support.

Referring now to the accompanying drawings in which like numerals and letters of reference indicate like parts in all the figures, 1 designates the bed frame of the hoisting drum mechanism on which the usual standard bearings 2 are carried, the bearings 2 receive the drum shaft 3 on which

the drive gear 4 is secured. The gear 4 is driven from any suitable source of power 55 through a chain 5 or the equivalent structure.

6 is cable drum on which the cable 31 that carries the well drilling tool is wound, the drum 6 being secured to turn with the shaft 60 3 and has a brake hub 7 around which a brake band 8 passes, the brake band 8 having one end 9, fixed and its other end 10 secured to the arm 11 of a brake operating lever 13 which is mounted in bearings 12 on 65 the bed plate of the machine.

14 designates a master worm gear secured to the shaft 3, and drum 6 at one side and the master gear 14 meshes with a worm 21 on a worm shaft 19 which has a ball end 18 70 to operate in the ball socket 20 of a bearing 17 that is supported on a bracket 15 on the bed frame 1 of the machine. A second bracket 15 opposite the first bracket 15 supports a standard 16 in which the rise and 75 fall bearing block 22 is mounted, the block 22 having lateral projections 23 whose edges are curved and fit into the runways of the standard 16, the bearing block 22 being secured in either of its upper or lower positions by set screws 25 that pass through either the upper or lower apertures 27 and 29 respectively of the standard 16.

On the front end the shaft 19 carries a hand wheel 29^a on which is the crank 30 85 through the medium of which the worm shaft 19 may be turned.

In practice the cable 31 is wound up on the drum 6 by the power applied through the chain 5 after which the brake band 8 is gripped onto the hub 7 to hold the drum 6 90 stationary. The operator then lowers the worm 21 into engagement with the gear 14 and locks the bearing 22 by the screw 25, after which the brake band 8 is released the 95 drum remaining stationary so long as the shaft 19 is not turned. The operator may now either let out on the cable 31 or take in on the cable 31 as much as desired by simply turning the hand wheel 29 thus it 100 will be seen that the speed of the cable 31 may be regulated to the smallest degree and insure the proper starting of the cutting apparatus.

From the foregoing description taken in 105 connection with the accompanying drawings

it is thought the complete construction, operation and advantages of my invention will be readily apparent.

Claim:

- 5 In an apparatus of the character described, a bed frame having main bearings, a drum shaft mounted in said bearings, a drum on said drum shaft, a master gear on said drum shaft, a pair of supports supported from said bed frame, a socket carried by one support a slide bearing carried by the other support, a worm shaft mounted
- 10

in said slide bearing and having a ball end mounted in said socket, a worm on said worm shaft to mesh with said gear, a hand wheel 15 for turning said worm shaft, and means for holding the said slide bearing in either of its positions to retain said worm in mesh with said gear or out of mesh with said gear as the case may be.

CLAYTON E. FREDERICKSON.
